UNITED STATES PATENT OFFICE

2,510,005

DEFLECTOR FOR REFRIGERATOR
DRIP PANS

Ralph B. Winship, Montreal, Quebec, Canada

Application November 1, 1946, Serial No. 707,275

3 Claims. (Cl. 62—17)

1

This invention relates to railway refrigerator cars of the top bunker type wherein the refrigerant is carried in containers located immediately below the roof and adjacent the side walls thereof. Such cars are provided with hatches through the roof of the car, said hatches being located above the containers for access to and servicing of said containers, and it is necessary, ordinarily, to equip said cars with inside carlines and purlins to support said containers and the load of refrigerant therein. Said cars are also provided with drip pans located closely below the containers to catch the drip therefrom or the liquid from overflow. Flues are preferably associated with or formed in part by the side walls of the car, and the metallic sheets forming said flues extend between the spaced metallic side wall posts, said flues conducting cooled air from the space around the refrigerant container to the lower part of the lading compartment. When salt is used with the ice to cause lower temperature the brine resulting from the melting ice and salt upon contacting the side wall posts causes rapid corrosion and disintegration and, therefore, it is the principal object of the present invention to provide means to prevent said brine from contacting said posts.

Also since the vertical edges of adjacent flue sheets are joined together opposite said posts, if such brine contacted said vertical seam, corrosion would be more rapid which would cause breaks in the flue sheets and consequent leakage of said brine into the car insulation so that it would come in contact with other metallic parts of the car.

More specifically the invention comprises a deflector or baffle associated with the drip pan of a refrigerator car to prevent brine from reaching said posts or the vertical seams of adjacent flue sheets.

Other objects and advantages of the invention will appear in the following description thereof.

In the drawings:

Figure 1 is a transverse section, partly broken away, of a refrigerator car embodying my invention.

Figure 2 is a top plan view of a portion of the outer margin of a drip pan showing my improved deflector applied thereto.

Figure 3 is a front elevation of the improved deflector.

The general parts of the refrigerator car shown are insulated roof 2; side walls 3; floor 4; hatches 5; refrigerant container 6; side wall flues 7; foraminous floor rack 8 and space 9 between the rack 8 and floor 4. The refrigerant container 6

is positioned directly below the roof 2 and adjacent the upper part of side wall 3. A drip pan 12 is provided below the container 6, and an upstanding partition 14 is provided along the inner edge of drip pan 12. The drip pan 12, and partition 14, cooperate with the roof 2 and side wall 3 to form an enclosing structure around the container 6, thereby providing a cooling compartment surrounding container 6. The side wall construction comprises inner 24 and outer 25 side plates, inner 27 and outer 28 side sills, outer posts 30 extending between and secured to the outer plate 25 and outer sill 28, and inner posts 31 extending between and secured to inner plate 24 and inner sill 27. A lining 33 is secured to the inner surface of the inner posts 31 and flue sheets 34 are interposed between the lining 33 and the posts 31, which flue sheets have outwardly projecting panels 36 formed therein to provide the side wall flues 7. Outer edge of drip pan 12 is secured to upper edge of lining 33 and partition 14 is secured to carlines 39, which carlines 39 extend between the side walls of the car and also support containers 6.

25 The improved deflector is shown at 40 and is formed from preferably a single piece of triangularly shaped sheet metal, bent along a medial line 41 from the vertex to the base, thus forming two triangular faces 42 and 43 having a common vertex 44. Flanges 45 are formed along the free side of each triangular face 42 and 43, which flanges are secured to the upper surface of drip pan 12, as by spot welding. It will be noted in Figure 2 that the deflector 40 is positioned with its base closely adjacent and opposite the inner wall post 31 and with the vertex 44 pointing toward the center of the car.

Thus any moisture dripping upon or flowing down the inclosed drip pan will be deflected in its course to opposite sides of the posts 31, it being understood that there is such a deflector adjacent each post. The base of the deflector is amply wide so as to divide and direct the liquid flowing on the drip pan laterally well beyond the side posts and into the adjacent flues 7.

45 Obviously the flanges 45 are not absolutely essential to the proper functioning of the invention, but are a convenience in the application of the deflector to the drip pan, as by spot welding.

Also it will be apparent that the deflector may have any upwardly arched form, such as that of a hollow semicone, but it is preferred that said deflector have substantially triangularly shaped sides which are contiguous along one of their edges and diverging toward their other edges and

having a common apex. The arching of the deflector also is sufficiently high so that when, for example, the refrigerant containers are drained of the spent brine and flushed, such large volume of liquid will also be adequately deflected and kept from contact with the car wall posts, as above described.

The accompanying drawings illustrate the preferred form of the invention, though it is to be understood that the invention is not limited to the exact details of construction shown and described, as it is obvious that various modifications, thereof, within the scope of the claims, will occur to persons skilled in the art.

I claim:

1. A drip handling structure for receiving the drip from an overhead ice bunker of a railway car, said structure comprising a pan and a drip deflector projecting from a surface thereof, said deflector being formed to provide two triangular sides diverging from a common fold line toward said surface of the pan, said sides having their bases adjacent one edge of the pan and having a common apex located inwardly of said edge, and said fold line inclining downwardly from said bases toward the apex thereof.

2. In a refrigerator car having a wall, a roof, a refrigerant container below said roof and adjacent said wall, a post within said wall, flues on opposite sides of said post formed in part by said wall, and a drip pan below said container sloping downwardly toward said wall to drain liquid falling thereon from said container into said flues; means to prevent moisture upon said drip pan from contacting said post, said means comprising

5
ing a drip deflector projecting from a surface of said pan, said deflector formed to provide two substantially triangular sides diverging from a common fold line towards said surface of said pan, said sides having their bases adjacent a post and a common apex located inwardly of said post, and said fold line inclining downwardly from said bases toward the apex thereof so as to deflect moisture flowing on said pan into the flues on opposite sides of said post.

3. A refrigerator car having a wall, a roof, a refrigerant container below said roof adjacent said wall, a post within said wall, a flue formed in part by said wall, a drip pan below said container sloping downwardly toward said wall to drain liquid from said container into said flue; means to prevent moisture upon said drip pan from contacting said post, said means comprising a drip deflector projecting from a surface of said pan, said deflector being formed to provide two triangular sides diverging from a common fold line towards said surface of the pan, said sides having their bases adjacent a post and having a common apex located inwardly of said post, and said fold line inclining downwardly from said bases toward the apex thereof.
